C. A. ERDMAN

AUTOMOBILE CURTAIN ATTACHMENT

Filed June 20, 1925

UNITED STATES PATENT OFFICE.

CARL A. ERDMAN, OF BIXBY, OKLAHOMA.

AUTOMOBILE CURTAIN ATTACHMENT.

Application filed June 20, 1925. Serial No. 38,530.

This invention relates to automobile accessories and pertains particularly to a device for stiffening or rigidly holding automobile side curtains to prevent the flapping or tearing of the same.

The primary object of this invention is the provision, in a manner as hereinafter set forth, of a device adapted to be fixed to the edges of the side curtains when the same are up, and to and between the top of the machine and the sides thereof to hold the edge of the curtain rigid to prevent the flapping and possible tearing of the curtain by the wind, when the machine is in motion.

15 The invention contemplates the provision of a telescoping stiffening rod having slots through each end thereof, one being adapted to be fitted over the curtain button normally positioned upon the outer side of the tonneau of an automobile, and the slot in the other end of the rod being adapted to fit over the curtain button which is normally placed upon the inner edge of the side frame of the automobile top. Intermediate the ends the rod 20 is provided with a series of adjustable outwardly extending buttons which are adapted to pass through button holes in the free edge of the side curtains, when the same are in position to secure the edges to the brace rod. 25

20 The edge of the curtain is thus held rigid and cannot be whipped about by the wind blowing thereagainst, when the car is in motion.

The invention will be best understood 30 from a consideration of the following detailed description taken in connection with the accompanying drawing forming a part of this specification with the understanding that the invention is not confined to any 35 strict conformity with the showing of the drawing but may be changed and modified so long as such changes and modifications mark no material departure from the salient features of the invention as expressed in the 40 appended claim.

In the drawing:—

Figure 1 is a central longitudinal sectional view through the device embodying this invention and through a pair of curtains secured thereto, showing the manner in which the brace is secured to the top and tonneau of an automobile.

Figure 2 is a plan view of the device.

Figure 3 is an enlarged detail of one end 55 of the brace rod showing the means employed for holding the rod tightly upon the

supporting button, to prevent a rattling of the same.

Figure 4 is a longitudinal section through the structure shown in Figure 3.

Referring now to the drawing in detail wherein like numerals of reference indicate corresponding parts throughout the several views, the numeral 1 indicates a transverse section through a portion of an automobile tonneau which has upon the outer face thereof the usual curtain securing button 2. A section through a portion of the top is indicated at 3, the side frame 4 of which is also provided with a curtain securing button 5 upon the inner edge thereof.

As it is well known the automobile curtain of the flexible type is secured between the buttons 2 and 5 and these curtains at their overlapping edges are provided with buttons and button-holes, by means of which the said overlapping edges are secured together. These buttonholes are easily torn out, especially when the front sections of the side curtains are not in place when the rear sections are up, and to overcome the difficulty the present invention has been perfected.

The device embodying this invention comprises a pair of members 6 and 7, one thereof being longitudinally bored as indicated at 8 to receive one end of the other member. The members are thus made extensible and when connected together constitute the curtain brace structure indicated as a whole by the numeral 9.

The member 6 has a pair of longitudinally extending slots 10 and 11 therethrough, the slot 10 being adjacent the upper end of the member as is shown and fixed to the member is a spring tongue 12 one end of which is enlarged and provided with the aperture 12' which overlies the slot 10 and when the button 5 is extended through this slot 10 it also passes through the tongue slot and the button bears against the tongue when turned, to prevent any movement of the member 6 on the button.

Extending through the other slot 11 is the shank of a shiftable button 13 which shank has a pair of collars 14 thereon which are located on either side of the member 6 and serves to retain the button in slidably position in the slot 11.

The lower member 7 also has a series of slots therethrough, here shown as three in number and indicated by the numerals 15 and 16. Fixed to the lower member is a

spring tongue 17 having the enlarged free end 17' which overlies the slot 15 and is provided with the aperture 17² which aligns therewith. The button 2 extends through the tongue, which as shown is between the curtains and the member 7, and when turned bears against the curtain forcing it against the spring and preventing the member from moving upon the button.

10 Extending through each slot 16 is the shank of a shiftable button 18 which carries a pair of spaced collars 19 thereon one on each side of the member 7, to hold the button shank in its respective slot.

15 When the brace structure embodying this invention is placed into use, the curtains indicated by the numeral 20 are first secured over the buttons 5 in the frame of the automobile top and then the button is extended 20 through the aperture 10 in the end of the member 6 and the outer end of the button is turned at right angles to retain the elements upon the button. The lower end of the member 7 is then positioned over the button 2 and the curtains placed thereover whereupon the end of the button 2 is turned 25 at right angles to secure this curtain and the lower end of the member 7 in position upon the button upon the vehicle body. The

30 other buttons 13 and 18 are then extended through the adjacent button holes in the curtains 20 and turned to retain the curtains

thereon whereupon the free edges of the curtains becomes securely fastened to the brace bar and are held rigid thereby.

35 From the foregoing description it will be readily seen that there has been provided a much needed and serviceable device for use in connection with automobile side curtains.

40 Having thus described my invention what I claim is:—

In an automobile having the body and top thereof provided with side curtain securing buttons, a side curtain attachment comprising 45 an elongated bar formed in two sections and having telescopic connections between the ends thereof, each section having a series of slots formed therethrough, one slot being adjacent one free end of each section and adapted to engage over an adjacent button carried by said body and top to hold the rod in extension therebetween, a spring device 50 surrounding those slots through which buttons pass and receiving said buttons therethrough and engaging the same to hold said rod steady, and buttons shiftable held in the other of said slots and adapted to extend 55 through and hold the side curtains against flapping, when the curtains are in position.

56 In testimony whereof, I affix my signature hereto.

CARL A. ERDMAN.
